UNITED STATES PATENT OFFICE.

PERRY S. MARTIN, OF BROADWAY, VIRGINIA.

INCUBATOR-ALARM.

1,213,798.

Specification of Letters Patent. Patented Jan. 23, 1917.

Application filed February 25, 1913. Serial No. 750,690.

To all whom it may concern:

Be it known that I, PERRY S. MARTIN, citizen of the United States, residing at Broadway, in the county of Rockingham and 5 State of Virginia, have invented certain new and useful Improvements in Incubator Alarms, of which the following is a specification.

The invention relates to new and useful 10 improvements in incubator alarms, and more particularly to the circuit closure for the same.

An object of the invention is to provide a circuit closure which is controlled by the 15 temperature of the incubator, which circuit closure may be readily adjustable for balancing the moving parts and which circuit closure includes contact members capable of cooperating with a movable member for sounding an alarm when the temperature of the incubator reaches a predetermined low limit or predetermined high limit.

In the drawings: Figure 1 is a detail perspective view of my improved thermostatically controlled circuit closer, a portion being broken away to more clearly show its construction and operation; Fig. 2 is a diagrammatic view of the wiring used in connection with a gang of incubators each 20 equipped with one of my circuit closers showing the manner in which a single signal may be employed with any number of incubators and also showing a switch by means of which the operator or attendant can determine 25 whether the signal is caused by excessive heat or extreme cold; Fig. 3 is a fragmentary perspective view of a conventional form of incubator, parts being broken away to show the positioning of my circuit closer 30 within the incubator; Fig. 4 is a fragmentary sectional view of an incubator, showing the employment of a circuit closer of a somewhat modified type; Fig. 5 is a fragmentary elevation of a portion of the circuit closer 35 mechanism as illustrated in Fig. 4; Fig. 6 is a fragmentary sectional view of an incubator, showing the employment of a still further modified form of circuit closer and 40 also showing, diagrammatically, the manner of wiring the alarm system when employed with a single incubator; Fig. 7 is a sectional view of the circuit closer illustrated in Fig. 6, parts being broken away to permit the 45 showing of the same upon a somewhat en-

larged scale; Fig. 8 is a diagrammatic view, 55 showing how a system of two incubators may be wired when employing the circuit closer of the types shown in Figs. 6 and 7.

Corresponding and like parts are referred to in the following description and indicated 60 in all the views of the drawings by the same reference character.

In order to insure a clear understanding of my incubator alarm system as a whole, I will first describe the structure of the thermostatically controlled circuit closer proper employed in the system. This circuit closer, in its preferred form, namely that shown in Figs. 1 to 3 of the drawings, includes a substantially rectangular shaped supporting 70 base 10 of any suitable insulating material, preferably wood. A depending bracket 11 is secured to the back of this base adjacent one end and its free end is directed forwardly to extend beneath and support a thermostat 75 12 of the double wafer type in a horizontal position, as shown, the thermostat being secured to said extended end of the bracket. The upper and lower wafers 13 and 14 of this thermostat move toward and away from 80 each other under the influence of cold and heat, respectively, and the lowermost of these wafers is secured to the bracket, while a needle 15 is secured to and extends upwardly from the upper wafer. A U-shaped 85 bracket 16 is secured by one side to the front of the base in such a manner that the needle projects through an opening 17 in its intermediate portion, the other side of this bracket extending upwardly in parallel 90 spaced relation to the base 10.

An indicator 18, which also forms the thermostatically movable member of the circuit closer, includes a substantially elliptical body portion stamped from sheet metal to 95 provide marginal flanges 19 perforated to receive a diametrically extending pivot pin 20, the ends of which seat in horizontally aligned perforations formed in the opposite sides of the bracket 16. The blade or contact 100 forming portion of the indicator consists of an extremely flexible spring which is secured by one end to the body 18 of the indicator and which extends at right angles to the pivot thereof with its free end vertically 105 movable over a temperature scale 21 secured to or marked on the opposite end of the base 10.

Directly above the needle 15 and immediately in advance of the pivot 20 the body portion 18 of the indicator is reinforced and provided with a tapped bore for an adjusting screw 22 having a milled head 23 at its upper end and provided in its lower end with a conical socket to seat the point of the needle. The blade of the indicator is provided intermediate its length with a counterweight, preferably in the form of a screw bolt 24 and binding nuts 25, which serves not only as a counterweight but also as a means of attachment for a cord 26 carrying a strip of celluloid or other non-conducting material 27, the purpose of which will be later explained.

It will of course be apparent that the counterweight will keep the adjusting screw in engagement with the thermostat needle and therefore that any expansion or contraction of the thermostat will raise or lower the indicator. It will further be understood that by a suitable manipulation of the adjusting screw, the indicator may be set to exactly point to or extend over any one of the divisions upon the scale 21. The scale preferably runs from 98 degrees to 107 degrees and the normal temperature at which the incubator is to be kept will of course lie at some intermediate point as for instance 103 degrees, although different poultrymen differ as to the exact temperature best suited to the hatching of healthy chickens.

In installing the circuit closer in the incubator, the adjusting screw is turned to bring the indicator directly in line with that scale division which corresponds to the exact temperature within the incubator at the time of adjustment and it will therefore be clearly seen that any further adjustment of the indicator is entirely unnecessary as the indicator will, in connection with the scale, at any time give absolutely the correct temperature reading of the incubator.

Contact arms 28 and 29 are swingingly secured at one end to the base by screws or other suitable fastening devices 30 and 31, respectively, and the free ends of these arms extend over the scale 21 as shown, having laterally directed terminals 32 extending one above and one below the indicator blade and in position to be engaged by the blade upon sufficient swinging of the indicator. These contact arms may be swung to bring their free ends over any desired divisions of the scale and form, in connection with the indicator, the contacts of the circuit closer. In use, the contact arm 28 is generally set in such a position as to be engaged by the indicator when the temperature rises to 105 degrees, while the contact arm 29 is set to be engaged by the indicator when the temperature falls to 100 degrees, these being ordinarily considered safe limits

between which the temperature in the incubator should be maintained. These limits of course, however, may be altered to suit the owner.

Secured to that end of the base opposite the bracket 16, are a plurality of binding posts 33, 34 and 35. The binding posts 33 and 34 are electrically connected to the pivot pins 30 and 31 of the contact arms 28 and 29, respectively, in any preferred manner as by strips of copper or other conducting material, shown in dotted lines at 36 and 37, the ends of these strips being secured to the back of the base by the screws of the binding posts themselves. In like manner the binding post 35 is electrically connected with the bracket 11 which is in turn electrically connected with the bracket 16 by a bolt 38, the strip in this instance being indicated by the numeral 39. As the indicator is an electric conductor and as it is uninsulated from the bracket 16, this connection in effect forms an electrical connection between the binding post 35 and the resilient blade of the indicator.

An L-shaped bracket 40 is secured to one end of the base, preferably by one of the binding posts, as shown, and extends laterally from the base in such a manner that it may be readily attached to one of the walls of an incubator as shown in Fig. 3 of the drawings, in which 41 indicates the incubator and 42 the eggs contained in the incubator tray. As clearly shown in this figure, the circuit closer is so positioned that the lowermost wafer 14 of the thermostat practically rests upon the eggs and the temperature at which the alarm will be given is therefore the temperature of the eggs rather than the temperature in the upper portion of the egg chamber which may be several degrees higher.

Having thus described the circuit closer proper of my alarm system, I will now describe the wiring and operation of the system as a whole. In Fig. 2 of the drawings I have diagrammatically illustrated three of my circuit closers acting as a gang for three incubators, the circuits controlled by these circuit closers all passing through a single switch and when energized ringing a single bell. For the sake of clearness, in the description of the operation which is to follow, I will designate these circuit closers as A, B and C.

Secured either upon the bodies of the incubators themselves or upon a wall or other suitable support adjacent each incubator, is a base block 43 provided with spaced binding posts 44, 45, and 46. The signal or alarm device preferably used with my system, comprises an electric bell 47 which may be located at any desired distance from the incubators and which is usually mounted at some convenient point in the house.

of the owner. A switch 48 is also mounted near the bell, but in such a position as to be readily accessible and this switch includes a supporting base 49 having swingingly mounted contact arms 50 and 51, the pivots of which form binding posts for the line wires, as will be later explained. The free ends of these contact arms 50 and 51 are movable into and out of engagement with stationary contacts 52 and 53, respectively. These contacts 52 and 53 are connected by a conductor 54 and a conductor 55 preferably in the form of a wire, connects the conductor 54 with one of the binding posts 56 of the bell.

A wire 57 is connected by one end to the binding post 34 of the circuit closer A and by its opposite end to the binding post of the contact arm 50, being supported intermediate its length by connection with the binding posts 45 of each of the base blocks 43. Another wire 58 is similarly connected between the binding post 33 of the circuit closer A and the binding post of the contact arm 51, its intermediate portion being supported by connection with the binding posts 44 of the blocks 43. A wire 59 is connected by one end to the binding post 35 of the circuit closer A and by its other end to one pole of a battery 60, this wire also being supported by connection with the binding posts 46 of the blocks 43. A wire 61 connects the opposite pole of the battery with the binding post 62 of the bell. Wires 57', 58' and 59' connect the binding posts 34, 33, and 35 of the circuit closer B with the binding posts 44, 45 and 46 of the adjacent block 43, while similar wires 57'', 58'' and 59'' connect the binding posts 34, 33 and 35 of the circuit closer C with the binding posts 44, 45 and 46 of the adjacent block 43.

In operation, assuming that the incubators containing the circuit closers A, B and C are all in use and that the indicators of the circuit closers are properly adjusted, if the temperature in any one of the incubators rises above the danger mark for which its circuit closer is set, a circuit will be closed from the battery 60 through the wire 59, and, if B or C are the circuit closers affected through the wires 59' or 59'', to the indicator arm of the circuit closer, through this arm, through the contact arm 28 of the circuit closer, through the wires 58' or 58'' to the wire 58 and through this wire to the contact 51 of the switch 49 passing from this switch through the wires 54 and 55 to the bell and from the bell through the wire 61 back to the battery thus sounding the bell. On the other hand, if the temperature in any one or more of the incubators falls below the danger point for which its circuit closure is set, a circuit will be closed in like manner from the battery through the indi-

cator arm of the circuit closer, through the contact arm 29 of the circuit closer, through the wires 57' or 57'' and the wire 57 to the contact 50 of the switch 49 passing from this switch through the wires 54 and 55 to the bell and from the bell through the wire 61 back to the battery, thus sounding the bell. It will therefore be apparent that if the temperature becomes either too high or too low in any one or more of the incubators installed in the system, the alarm will be sounded, or, in fact, if the temperature should become too high in one incubator and too low in another, the alarm would still be sounded. The owner or attendant upon hearing the bell passes at once to the switch 48 and swings either of the contact arms 50 or 51 out of position. If upon swinging the contact arm 50 out of position the bell stops ringing, he at once knows that one or more of the incubators is too cold. On the other hand, if upon swinging the contact arm 51 out of position the bell stops ringing, he knows that one or more of the incubators is too hot. If the bell rings when the contact arm 50 is in position and the contact arm 51 is out of position, and also when the contact arm 50 is out of position and the contact arm 51 is in position, he knows that one or more of the incubators is overheated, while one or more of the remaining incubators is too cold. He then throws both contact arms out of position to save the battery and avoid continuous ringing of the bell and goes to attend to the incubators. A single glance at the indicator of each of the circuit closers will disclose which of the circuit closers is closed and whether it is closed because of too high a temperature or too low a temperature, and the heating system for that incubator may be adjusted to remedy the fault. In order to permit the immediate resetting of the system, in such a manner that it may give warning for the other incubators, while the incubator which has been adjusted is still too hot or too cold, because of not having had time enough to change its temperature, the attendant may place the strip of celluloid 27 between the blade of the indicator and that arm against which it is engaging thus breaking the circuit. Upon returning to his station or house, he may then reset both the contact arms 50 and 51, the celluloid strip effectually breaking the circuit in that circuit closer to which it is applied. As soon however, as any of the other incubators get out of order, the signal will be again given or if the circuit closer in the incubator, which has just been regulated should be operated to close the opposite circuit because of excessive regulation of the heating system, the alarm will be sounded. Moreover, as soon as the indicator arm of the circuit closer is moved out of engagement with the contact arm, the strip 27

27 will be released and will fall from the contact arm. For this reason, no further actual manipulation of the circuit closer is required as it immediately becomes automatic for both high and low temperatures again.

Although the circuit closer and wiring above described constitutes the preferred form of my invention, it will of course be understood that with certain types of incubators now on the market it would be impossible to use this form as there would not be sufficient space above the egg trays in the incubator for the proper positioning of the entire circuit closer. For this reason I have provided circuit closers of slightly modified forms, one adapted for attachment to the outer face of one side wall of the incubator and the other adapted for attachment to the outer face of the top of the incubator. These two forms are necessary as in some instances a continuous heating tank or drum extends across the top of the incubator, while in other cases the incubator, about its sides, is water jacketed or otherwise shut in. One or the other of these three forms may be employed with any type of incubator now on the market.

That form of circuit closer adapted for use upon the side of an incubator is clearly illustrated in Figs. 4 and 5 of the drawings and is substantially the same as that previously described, the chief difference consisting in the fact that the thermostat 12, instead of being supported as in the preferred form, is supported by one arm of a U-shaped bracket 65 which is carried by a sleeve 66 secured by one end to the opposite arm and through which a needle 67 of the thermostat extends, this needle being elongated to extend completely through the opposite end of the sleeve, which, in this case, is threaded into the opening 68 of the bracket 16 corresponding to the opening 17 of the same bracket in the preferred form of the invention. The indicator arm 18 is adjusted in the same manner with respect to the thermostat by the adjusting screw 22 and the remainder of the construction of the circuit closer is identical with that of the preferred form, with the exception that the counterweight 24-25 of the preferred form is replaced by an arcuate rod 69 secured by one end through the shorter arm 55 of the indicator and threaded at its opposite end to adjustably receive a nut 70, this arm extending substantially at right angles to the indicator arm. In employing this form of circuit closer, the sleeve 66 is passed outwardly through an opening formed in the wall 71 of the incubator and is threaded into the bracket 16 as shown in Fig. 4, the base of the circuit closer being secured to the outer face of the wall by brackets 72 corresponding to the bracket 40.

That form of circuit closer and indicating mechanism employed upon the top of the incubator is illustrated in Figs. 6 to 8 of the drawings and is almost identical in construction with the forms previously described. In this case however, the bracket 16 carrying the indicator arm is mounted upon the base at right angles to the position which it occupies in the other form and the blade portion of the indicator arm extends at right angles to the body portion as shown at 73, the body portion being provided at one end with an adjustable nut 74 forming a counterweight, this nut being threaded upon a screw 75. In this form of the invention, the thermostat 12 is supported in a bracket 76, identical in construction with the bracket 65 and carried by a sleeve 77 corresponding to the sleeve 66, the sleeve in this case extending through the top wall of the incubator and being threaded into the base of the bracket 16, while the needle 78 of the thermostat extends through the sleeve with its upper end beyond the same to be engaged by the adjusting screw 79.

It will be clearly apparent that the operation of all three forms of circuit closers above described is identical and that the same system of wiring is used. In Fig. 6 however, I have illustrated, diagrammatically, the wiring when the alarm is to be employed with a single incubator. In this wiring a conductor 80 connects the binding post 34 of the circuit closer with the contact arm 50 of the switch 48, a wire 81 connects the binding post 33 with the contact arm 51 and a wire 82 connects the binding post 35 with one pole of the battery 60. The remainder of the wiring is identical with that shown in Fig. 2 of the drawings and need not therefore be described.

In Fig. 8 I have illustrated diagrammatically the wiring of a system having two incubators, this wiring being identical with that shown in Fig. 2, with the exception that the blocks 43 are done away with, the lead wires from the circuit closer of the intermediate incubator being spliced directly to the wires between the switch and other circuit closer. Any further detailed explanation of this form of wiring is therefore unnecessary.

From the foregoing description, it will be apparent that I have provided an extremely simple and efficient form of circuit closer for use in incubator alarm devices and that this circuit closer may, by extremely slight structural changes, be adapted for use with any type of incubator now on the market. It will further be apparent that by employing this type of circuit closer and the three wire signaling system for which it is especially adapted, the usefulness and value of the signaling system as a whole is greatly en-

hanced, due to the fact that even before reaching the incubators the attendant or owner can determine whether the alarm is caused by excessive heat or excessive cold.

5 Moreover, by utilizing one member of the circuit closer as an indicator, any number of incubators may be included in the same system and the attendant may readily determine which incubator needs attention by 10 merely glancing at the indicator arm of its circuit closer. Furthermore, when once installed, absolutely no adjustment or regulation of the circuit closer or thermostat thereof is required, the only possible manipulation being the changing, as desired, of the danger points at which the alarm is to be given, this being accomplished simply by 15 swinging one or the other of the contact arms 28 and 29 of the circuit closer over the 20 scale.

Having thus described the invention, what is claimed as new is:

1. In incubator alarms, a circuit closer including a base, spaced brackets carried by 25 the base, a thermostat carried by one of the brackets, a needle carried by said thermostat and extending through the other bracket, an indicator arm pivoted in said latter bracket, a counter-weight carried by 30 the arm and normally holding the same in engagement with the needle, and contact arms adjustable toward and away from the indicator arm.

2. In incubator alarms, a circuit closer

including a base, brackets carried by the base, a thermostat carried by one of the brackets, a needle carried by the thermostat and extending through the other bracket, an indicator arm pivoted in said latter bracket, an adjusting screw threaded through said arm and in alignment with the needle, a counterweight carried by the arm and normally holding the same with its set screw in engagement with the needle, and contacts adapted to be engaged by the arm upon 45 swinging movement thereof.

3. In incubator alarms, a circuit closure including a base, spaced brackets carried by the base and arranged one above the other, a thermostat carried by the lower bracket, a needle carried by the thermostat and extending through an opening in the upper bracket, an indicator arm pivotally supported by the upper bracket, an adjusting screw threaded through said arm and in alignment with the needle, a counter-weight carried by the arm and normally holding the same with its set screw in engagement with the needle and contacts adapted to be engaged by the arm on swinging movement thereof.

In testimony whereof I affix my signature in presence of two witnesses.
